(57) **CLAIM**

The ornamental design for a toothpick assembly, as shown and described.

DESCRIPTION

FIG. 1 is an upper perspective view of the toothpick assembly.

FIG. 2 is a front elevation view thereof, showing the first pattern of dashed lines and the second pattern of dashed lines;

FIG. 3 is a back elevation view thereof;

FIG. 4 is a side elevation view thereof;

FIG. 5 is an opposite side elevation view thereof;

FIG. 6 is a top end view thereof, showing the first pattern of dashed lines;

FIG. 7 is a bottom end view thereof, showing the second pattern of dashed lines;

FIG. 8 is another upper perspective view of the assembly in a closed configuration; and,

FIG. 9 is a side perspective view of an isolated toothpick removed from an interior of the assembly, showing the edges resulting from separation at the first pattern of dashed lines and the edge resulting from separation at the second pattern of dashed lines.

In the drawings, the broken lines depict perforations, which form a part of the claimed design.

1 Claim, 2 Drawing Sheets
